UNITED STATES PATENT OFFICE.

FREDERICK K. SMITH, OF NEW YORK, N. Y.

DESIGN FOR A BOTTLE.

Application filed March 27, 1924. Serial No. 9,077. Term of patent 7 years.

To all whom it may concern:

Be it known that I, FREDERICK K. SMITH, a citizen of the United States, residing at New York, in the county of New York and State of New York, have invented a new, original, and ornamental Design for a Bottle, of which the following is a specification, reference being had to the accompanying drawing, forming part thereof.

I claim:
The ornamental design for a bottle, as shown.

Signed at New York, in the county of New York and State of New York, this 19th day of January, 1924.
